UNITED STATES PATENT OFFICE.

WILLIAM C. KLEIN, OF ALLENTOWN, PENNSYLVANIA.

PNEUMATICALLY-CONTROLLED ELECTRIC SWITCH MECHANISM.

Application filed January 10, 1922. Serial No. 528,357.

To all whom it may concern:

Be it known that I, WILLIAM C. KLEIN, a citizen of the United States, residing at Allentown, in the county of Lehigh and 5 State of Pennsylvania, have invented certain new and useful Improvements in a Pneumatically-Controlled Electric Switch Mechanism; and I do hereby declare the following to be a full, clear, and exact description of the invention, such as will enable others skilled in the art to which it appertains to make and use the same.

This invention relates to a pneumatically controlled electric switch.

15 One object is to provide a novel construction particularly advantageously useful in registers of the type used in passenger cars for fare purposes.

A second object is to provide such a mechanism having a cylinder with a piston therein to coat under air pressure to close an electric circuit through an electro-magnet to actuate such register or other means.

Another object is to provide a suitable 25 valve in such a mechanism, which may function to control both the inlet and exhaust of compressed air.

A further object is to provide such a construction of housing wherein a plurality of 30 the switch devices, each associated with a different part to be operated, and utilize the same securing or mounting means.

Additional objects and advantages will 35 become apparent from a consideration of the description following taken in connection with accompanying drawings illustrating one practical embodiment and wherein:—

Figure 1 is a diagrammatic view showing 40 the improved switch mechanism in connection with a fare register installed on a passenger car, and the electrical connections;

Figure 2 is a side elevation of the switch mechanism alone and with one of the sides of the casing removed to disclose details;

45 Figure 3 is a front elevation of the switch mechanism with a part of the casing removed to disclose details, and

Figure 4 is a vertical sectional view taken substantially centrally through the pneumatic switch operating switch mechanism and on line 4—4 of Figure 3.

Referring specifically to the drawings, a register is shown at A installed on a car as conventionally illustrated at B, at any suitable location, for instance at the top of the bulkhead as usual. The particular register

illustrated is adapted to register the number of fares received at C and the number of transfers received at D, through any suitable means, controlled through actuation of 60 levers E and F, respectively, fulcrumed or pivoted at G and H.

Associated with the lever E is an electro-magnet which may be a solenoid as at 10 having its core 11 operatively connected at 65 12 to the lever E. A solenoid 13, similar to solenoid 10 is provided for lever F and its core at 14 is connected to the lever F as at 15.

In order to control actuation of the sole- 70 noids 10 and 13, electric switch mechanism of any approved type is provided. The instance shown consists of a casing at 16 disposed at any suitable location and particularly including a panel or mounting 75 17 disposed vertically and equidistantly of the sides in order to provide compartments 18 and 19. In each compartment 18 and 19, a block of insulation as at 20 is provided, preferably being slightly inclined as shown 80 and secured to the panel 17 by means of screws 21. A spring leaf forming a contact is provided at 22, one at each end of each block 20, being fastened thereto in any suitable manner by means of screws 23. These 85 contacts may have fastened thereto in any suitable manner conducting heads at 24.

A switch arm is provided in order to bridge the contacts 22 and it may consist of an arm or bar 25 pivoted at 26 to a plate 90 or bracket 27 fastened at 28 to the panel 17. Bar or arm 25 has a block 29 of insulation fastened thereto and which is provided with a curved or arcuate conductor 30 screwed thereto as at 31. The conductor 30 is adapted to bridge the contacts 22 to close electric circuits through the solenoids 10 and 13, respectively.

Both of the solenoids 10 and 13 have one terminal as at 32 and 33 ground at 34. The 100 other terminal or pole of the magnet 10 by means of a conductor 35 is secured to one of the contacts 22 while the opposed contact 22 has a conductor 36 leading therefrom and connected to a conductor 37 leading to a conductor wire for the trolley of the car B in order to complete a circuit through the magnet 10.

A conductor 38 leads from the opposite pole or terminal of the solenoid 13 to the 110 terminal 32, and to a contact 22 of the other switch while the complementary contact 22

has a conductor 39 leading therefrom and connected to the wire 37 leading to the trolley wire aforesaid.

It will thus be seen that when the conductor 30 engages the conductors 22 in the circuit of solenoid 10 that such solenoid will be actuated in order to throw the lever B to operate the cash registering mechanism. Also it will be realized that when the conductor 30 for the contacts 22 in the circuit of the solenoid 13 are engaged, an electric circuit is established through the solenoid 13 actuating the lever 12 which operates the transfer registering mechanism at B.

15 The switch arms 25 are adapted to be thrown or controlled pneumatically and in order to accommodate the pneumatic means, casings 40 are provided one in chamber 18 and one in chamber 19. A pipe 41, in communication with any suitable source of compressed air under control of a cut off valve at 42, is connected as at 43 to the casings 40. Each casing 40 is provided with a bore forming a cylinder at 44 in which a suitable type of piston 45 operates, which preferably has packing at 46 to wipe the wall of the bore 44 and from which piston a rod 47 extends being pivoted at 48 to a link 49 in turn pivoted at 50 to the arm 25.

20 The lower end of the bores 44 are closed by screw plugs 51 and they have openings in which the rods 47 are disposed and slidably mounted. A passageway for the supply of compressed air is provided at 52 communicating with the bore 44 and leading from an enlargement or bore at 53 in direct communication with the branch 43. The escape of compressed air from the pipe 41 through the branches 43 to the bore 53

25 is normally prevented by the engagement of a valve at 54 against a seat 55 and which valve is urged toward said seat by an expansive spring at 56 abutting the valve 54 and a screw plug 57 which is employed to enclose the lower end of the bore 53.

30 Pressure within the bores 44 may be relieved through ports 58 in advance of the piston 55. Exhaust of the compressed air may escape from the passageway 52 through a port 59 in communication therewith and with a chamber 60 from which a port 61 leads exteriorly of the casing. Within the chamber 60 a valve seat is provided at 62 which may be engaged by a valve portion 53 provided on a stem 64 which is depressible or slidable through the casing and a screw plug 65 provided in the chamber 60. A stem 66 extends from the valve portion 63 into the passageway 52 and rigidly connects the valve 54 to the stem 64. Each of the stems 54 may have operating heads or knobs 67 thereon.

35 The casing 40 may be secured in place in any suitable manner by means of bolts 68 passing through ears 69 on such casings

and through the panels 17. Connected with the arms 25 are contractile coil springs 70 which are also connected as at 71 to a suitable pin mounted in the panel 17.

In operation, when it is desired to actuate the lever E, solenoid 10 is energized upon depression of the appropriate button 67 which moves valve 54 from its seat enabling compressed air supplied through the pipe 41 to enter through the appropriate branch 43 into the passageway 52 and cylinder 44 moving the piston 45 downwardly causing throwing of the arm 25 and engagement of the conductor 30 with the proper contacts 22 of the switch. After depression of the button 67, it is released, whereupon spring 56 restores valve 54 against its seat cutting off the supply of compressed air and raising the valve portion 63 from its seat enabling the compressed air to escape from the cylinder 44 through the passageway 52, port 59, chamber 60 and port 61. Spring 70, which has been tensioned by the movement of the arm 25 into switch closing position will thereupon operate to restore the switch arm 25 to a normal or elevated position.

It will be realized that the actuation described is similar for the registering mechanism at D controlled by the solenoid 13 upon depression of the appropriate button 67 therefor.

It is to be understood that the switch is capable of broad use and that I do not limit myself to its use in connection with even a register or to the use of a plurality of switches, since in many instances a single switch can be used and the invention still practised.

Buttons at 67 have been shown by way of example only, as any desired means may be employed to control the valves 54 and valve portions 63, for instance by a foot lever, a cord or otherwise.

Additional changes may be resorted to within the spirit and scope of the invention as defined by appended claim.

I claim as my invention:—

An operating mechanism for an electric switch having a body provided with a cylinder extending inwardly from one end and terminating short of the other end, closure means for the open end of the cylinder, a switch-closing means having a piston operable in said cylinder whose rod extends slidably through said closure means, said body having a supply chamber for power fluid at one side of said cylinder, said body having an exhaust chamber for power fluid substantially in alignment with the supply chamber, said chambers extending inwardly from opposite ends of the body, plugs closing the open ends of said chambers, said chambers being spaced apart at their inner ends, said body having a tortuous pas-

- sageway extending partially longitudinally of and between the cylinder and exhaust chamber including a branch extending from the supply chamber to the cylinder, said 5 passageway having a port extending from the exhaust chamber substantially in line with said branch, a depressible stem extending through one of said plugs, valves carried by said stem and one in each chamber, said valves being adapted to coact with the branch and port, each valve being adapted to close as the other valve is opened, and a spring in the supply chamber resting on the plug thereof to normally urge the valve therein to closed position. 15
- In testimony whereof I affix my signature in presence of two witnesses.
